UNITED STATES PATENT OFFICE.

WILLIAM DEVAUN, OF SOUTHPORT, NORTH CAROLINA.

COMBINATION-WRENCH.

SPECIFICATION forming part of Letters Patent No. 595,289, dated December 14, 1897.

Application filed September 3, 1896. Serial No. 604,787. (No model.)

To all whom it may concern:

Be it known that I, WILLIAM DEVAUN, a citizen of the United States, residing at Southport, in the county of Brunswick and State of North Carolina, have invented certain new and useful Improvements in Combination-Tools; and I do hereby declare the following to be a full, clear, and exact description of the invention, such as will enable others skilled in the art to which it appertains to make and use the same.

My invention relates to a combination-tool which includes a nut and pipe wrench, screw-driver, and metal shears. The particular parts and construction of my invention will be fully pointed out in the specification following, reference being had to the accompanying drawings, forming a part thereof, in which—

Figure 1 is a view of my device closed. Fig. 2 is a view of the same open.

This device consists of the two levers A and B, pivoted near one end at C. The short ends B' of these are formed as curved jaws, cross-grooved upon their inner surfaces and adapted to be used as pipe-tongs or as a wrench to grasp a nut. The portion of the long arm of the lever or handles which lies next to the pivot is formed as a pair of sheet-metal shears having cutting edges E, which have sliding contact, as a pair of shears. The outer end of one or both of these levers is formed as a screw-driver.

This device is simple and strong in its construction and can be manufactured cheaply and is capable of a wide range of uses. It is useful and substantial and not likely to be broken.

By reference to the drawings it will be observed that the cutting portions E are formed with segmental cutting edges, the curvatures

of which commence in proximity to the pivot-point C. By this means should the wire being cut be placed too near the pivot the closing of the respective arms or levers A B will force the wire to the proper cutting-point before the cutting operation commences. By this means the cutting always takes place at approximately the same point, the arrangement of said segmental edges being such that this cutting-point is the proper distance from the pivot-point to secure the greatest amount of power in relation to the levers A B. One of said levers B is provided near its outer end with a handle or loop D, whereby the tool may be held firmly by four fingers and the thumb left free to operate the opposing lever.

Having thus described my invention, what I claim as new, and desire to secure by Letters Patent, is—

In a combination-tool, the combination with a pair of pivoted levers having segmental ends provided with lateral corrugations for forming a pipe-wrench to one side of their pivot and straight cutting portions having concave cutting edges to the opposite side of their pivot and screw-driver ends, of a pivot-pin connecting said levers, and a handle or loop mounted on the side of one of said levers away from the screw-driver end and adapted to receive the hand whereby one of said levers may be lifted by a portion of the fingers while the remainder are free to operate the opposing lever, substantially as described.

In testimony whereof I have signed this specification in the presence of two subscribing witnesses.

WILLIAM DEVAUN.
